DESIGN FOR A BABY BATHING DEVICE

Irving Brecher, Flushing, N. Y., assignor to Baby World Company, Inc., New York, N. Y., a corporation of New York

Application October 29, 1946, Serial No. 134,366

Term of patent 3½ years

(Cl. D4—4)

To all whom it may concern:

Be it known that I, Irving Brecher, a citizen of the United States, residing at 75—02 190 Street, Flushing, L. I., in the county of Queens, city and State of New York, have invented a new, original, and ornamental Design for a Baby Bathing Device, of which the following is a specification, reference being had to the accompanying drawing, forming part thereof.

In the drawing:

Fig. 1 is a side elevational view of a baby bathing device, showing my new design;

Fig. 2 is a top plan view thereof;

Fig. 3 is a side elevational view showing the device in an inverted position; and

Fig. 4 is a front elevational view of the device.

I claim:

The ornamental design for a baby bathing device, substantially as shown.

IRVING BRECHER.
